UNITED STATES PATENT OFFICE.

THOMAS DE LA MARE, OF SALT LAKE CITY, UTAH.

PROCESS AND APPARATUS FOR REPAIRING PAVEMENTS.

Application filed April 1, 1925. Serial No. 19,832.

My invention relates to concrete construction, and has for its object to provide a new and economical method of repairing concrete pavement and the apparatus by which my method is carried out.

These objects I accomplish by my improved method, and with the apparatus illustrated in the accompanying drawings in which similar letters and numerals of reference indicate like parts throughout the several views, and as described in the specification forming a part of this application and pointed out in the appended claims.

In the drawings Figure 1 is a plan view of a casing reinforcement forming a portion of one repair block. Figure 2 is a plan view of the metal sheet used to hold the curving strips in place. Figure 3 is an inverted plan view of the shield or guard plate. Figure 4 is a longitudinal section of the assembled apparatus before the concrete is poured therein. Figure 5 is a plan view of the guard plate used in making the repairs in the concrete used at the frogs of railway tracks. Figure 6 is a plan view of the guard plate used in making repairs in concrete adjacent a curve in railway tracks. Figure 7 is a plan view of the guard plate used in making repairs adjacent a curve in railway tracks, and used on the opposite side of the track from the one shown in Figure 6. Figure 8 is a longitudinal section on line 8—8 of Figure 7, with the concrete in place therein.

When concrete is poured thin enough to fill all of the voids therein the plastic mass must be allowed to take at least the initial set before it is disturbed, and it does not fully set for several days thereafter. In the use of cement concrete for street and road paving, and specially in cities where traffic is great, the street paving concrete must be protected until it has set before traffic can be resumed, or the blocks of concrete must be made and allowed to set before they are laid, otherwise the concrete will be crushed and become worthless as a pavement. My process is a method by which concrete paving blocks may be more thoroughly reinforced by adding to the commonly used reinforcements, a casing made of sheet metal having a perforated bottom and side walls to give additional strength to the finished paving block, and to also protect the block in order that it may be made and laid in one operation and traffic over the pavement re-

sumed as soon as the concrete is poured. Also to give a form to concrete blocks as constructed by my method which said blocks to be used contiguous the rails of street rail- 60 ways at the frogs and curves in said tracks as well as where the tracks are straight. And to allow repairs to be made in the edges of paving adjacent the rails whereby that portion of the paving which covers or is above 65 the cross ties or the end portion of the ties may be removed and replaced by my reinforced concrete blocks constructed in accordance with my invention, and without the delay commonly required for setting of the 70 concrete. Also to allow repairs to be made in concrete paving and not impede traffic thereover except while pouring the concrete, and by my method to allow the full setting of the concrete without the usual delay in 75 traffic.

My method of repairing concrete pavement is to pour plastic cement concrete into a sheet metal mold or casing 1, having a perforated bottom and side walls. Reinforcing wire 2 is passed through holes in the sides of said casing and fastened medially in place. Then placing said mold 1 in the position where the repair in a pavement is to be made, I fill it with plastic cement concrete. The side walls taper inwardly toward each other and the space between adjacent walls is filled with plastic asphalt. When the top of said plastic mass is struck or leveled a thin piece of light fabric, such 90 as sheeting is spread over the upper face of the plastic mass and a similarly shaped thin metal sheet 4 having countersunk holes 5 therein, is placed on said sheeting. Threaded holes 6 are bored in the corners of said sheet 4 to fasten a metal guard plate 7 to said sheet 4, and on the guard plate a marginal rib 15 is provided to engage over the edges of said sheet 4. A piece of burlap or coarse fabric 11 is placed between said sheet 100 4 and the guard plate 7. The said guard plate 7 has countersunk holes 8 therein some of which are adapted to be in alinement with the holes 5 of the sheet 4 when said guard plate is secured thereto, and said holes 5 and 105 8 are to allow water to reach the concrete block and keep it moist during the setting time. Holes 9 are bored through the said guard plate 7 in alinement with the holes 6 of the sheet 4, and through which the shanks 110 of hook eye 10 are passed to fasten the sheet 4 and guard plate 7 together for lifting and

removing them from over the concrete patch when it has fully set. The edges of said guard plate 7 are beveled to allow traffic to pass thereover when it is in use to protect the 5 concrete patch during the setting period.

In Figure 5 I have shown a modification as to the form of the apparatus, which form is used at frogs in the tracks of railways in city streets, and in Figures 6 and 7, I have 10 shown modifications as to the form of the apparatus to be used at curves of tracks.

In using my method of repairing concrete pavement not contiguous to railway tracks, the crushed or otherwise damaged 15 pavement is dug away and the metal reinforcement is placed in said hole, the plastic concrete is then poured into and filling the hole and pounded to closely surround the reinforcement and on the same plane as the 20 surrounding pavement, the fine meshed fabric 3 is spread over the freshly poured concrete, and the thin metal sheet 4 is placed over the said light or fine fabric with the countersunk holes 5 flared upwardly, and 25 then guard plate 7 placed on the thin sheet 4 with its downwardly flanged edge fitting over the margin of said sheet 4, and with the holes 8 in alinement with some of the holes 5 of the sheet, as shown in Figure 8. When 30 the concrete has had its initial setting, the hook eyes 10 are screwed into the threaded holes 9 of the guard plate and said plate is removed and a piece of burlap or other coarse mesh fabric is placed between the 35 sheet 4 and plate 7, and the guard plate replaced over the sheet 4, and water may be then poured or allowed to flow through the alined holes 8 and 5 to keep the fabrics and concrete moist until final setting has taken 40 place. Then by screwing the said hook eyes 10 into both the sheet 4 and plate 7 the apparatus may be removed for use elsewhere. The said hook eyes 10 are used only when it 45 is desired to remove one or both of said sheets. By using one or more of said sheets 4 and plates 7, placed edge to edge, any sized patch or repair may be made in a pavement. The same steps and method of procedure is used when repairing along the 50 tracks of street railways, using the required modified forms of apparatus shown in Figures 5, 6 and 7 as required. Heretofore when laying pavement adjacent the rails of tracks brick, stone blocks, and concrete 55 blocks have been laid as a part of the pave-

ment and in replacing the cross ties to which the rails are secured, such brick, or blocks must be removed before the old ties can be taken out and new ties placed under the rails. The ballast around and under 60 the cross ties must also be taken out, and to do such work the traffic over the pavement must be stopped and the holes in the pavement guarded. With my improved method and apparatus the repairs may be easily 65 and quickly made by taking out one or more of the reinforced concrete blocks, and replacing it, first by placing the metal mold 1 across and resting on the ends of two or more ties and pouring the plastic concrete 70 therein, and protecting and curing the concrete by the fabric, sheet 4 and guard plate 7 as fully set out above.

Having thus described my method and the apparatus by which it is carried out I 75 desire to secure by Letters Patent and claim:

1. A method of repairing pavement which consists of placing a sheet metal mold having reinforcing wires secured through its 80 wall in the hole of the pavement, then pouring plastic concrete into said mold and enough to fill the hole in the pavement to its general face, curing said concrete by moisture applied on its upper face and held contiguous its sides and lower face, and protecting the upper surface of said concrete 85 from injury thereto until it has fully set.

2. A method of repairing pavement consisting of filling the hole in pavement with 90 plastic concrete, placing a thin porous flexible sheet over the said plastic concrete, covering the said flexible sheet with a perforated thin metal sheet, placing another porous sheet on the upper face of said metal sheet, 95 and securing a perforated guard plate to said metal sheet.

3. A method of repairing pavement which consists of filling a hole in pavement with plastic concrete, placing a flexible porous 100 sheet over the said plastic concrete, covering said flexible sheet and a margin of the pavement around said hole with a perforated guard plate and gradually curing said plastic concrete by moisture supplied through 105 the perforations in said guard plate.

In testimony whereof I have affixed my signature.

THOMAS DE LA MARE.
